US0D1090857S

(12) **United States Design Patent** (10) Patent No.: **US D1,090,857 S**
(45) Date of Patent: **** Aug. 26, 2025**

(54) **MEDICAL DIAGNOSTICS DEVICE**

(71) Applicant: **Onera Technologies B.V.**, Eindhoven (NL)

(72) Inventor: **Peter Cramer**, Eindhoven (NL)

(**) Term: **15 Years**

(21) Appl. No.: **35/518,821**

(22) Filed: **Sep. 25, 2023**

(80) **Hague Agreement Data**

Int. Filing Date: **Sep. 25, 2023**

Int. Reg. No.: **DM/232486**

Int. Reg. Date: **Sep. 25, 2023**

Int. Reg. Pub. Date: **Oct. 27, 2023**

(51) **LOC (15) Cl.** **24-02**

(52) **U.S. Cl.**

USPC **D24/186**
